UNITED STATES PATENT OFFICE.

ORVILLE T. WEISER, OF PHILADELPHIA, PENNSYLVANIA, ASSIGNOR TO SIEGMUND LUBIN,
OF PHILADELPHIA, PENNSYLVANIA.

MOVING-PICTURE-PROJECTING MACHINE.

No. 881,512.

Specification of Letters Patent. Patented March 10, 1908.

Application filed March 21, 1907. Serial No. 363,552.

To all whom it may concern:

Be it known that I, ORVILLE T. WEISER, a citizen of the United States, and resident of Philadelphia, in the county of Philadelphia and State of Pennsylvania, have invented 5 certain Improvements in Moving-Picture-Projecting Machines, of which the following is a specification.

This invention is a moving picture projecting machine comprising means for covering and uncovering the aperture through which light is passed from the lantern to throw upon the screen the pictures on the film moving past the aperture, and means for adjusting 10 the film with relation to the aperture.

Objects of the improvement are to properly adjust the relation of the aperture and the pictures upon the film traveling through the machine and to shield the film against 15 flame from the lantern and other sources.

Further objects are to provide for the periodic obstruction of the light by a shutter moving at right angles across the light aperture and to simplify the general mechanism 20 of the machine.

In the accompanying drawings, Figure 1 is a side elevation of a machine embodying my improvements; Fig. 2 is a front elevation of the same with parts broken away for 25 clearer illustration, and Fig. 3 is a rear sectional elevation with parts removed for clearer illustration.

As shown in the drawings, the machine frame 1 carries the journaled hollow driving 30 shaft 2 having fixed thereon the spur wheels 3 and 4. A shaft 5 is movable longitudinally within the shaft 2 and is fixed so that it cannot revolve relatively thereto by means of the screw 6 passing through the slot 7. The 35 screw 6 fixes to the rod 5 a sleeve 8 movable longitudinally on the hollow shaft 2, the sleeve having a hub 9. A coiled spring 10, held at one end by the bearing 11 fixed to the shaft 2 and engaging at the other end the 40 screw 6, acts to move the sleeve with the shaft to which it is fixed in the direction of the arrow. A coiled spring 12 in the hub 9 is adapted for acting against a disk 13 on the shaft 2, the movement of the sleeve toward 45 the disk causing the latter to be forced against a wheel 14 normally loose on the shaft 2 and adapted to be clutched between the disk 13 and a disk 15 fixed on the shaft. 50 A handle 16, counterbalanced by a weight 55 17 adjustable on a rod 18, is longitudinally

fixed to and movable revolvably on the rod 5. The handle has a hub 19 revolvable on a bushing 20, which is fixed to the wheel 4, and a cam way 21 containing a pin 22 fixed to the bushing. In this construction, when 60 the handle 16 is turned in the direction of the arrow, the engagement between the cam way 21 and the pin 22 causes the shaft 5 and the sleeve 8 to move longitudinally, with the result that the wheel 14 is gripped between 65 the disks 13 and 15. When the handle is released the spring 10 moves the shaft 5 and sleeve 8 in the reverse direction to release the wheel 14.

A chain 23 is fixed at one end to the wheel 70 14 and at the other end to an arm of a lever 24 having the fulcrum 25. The other arm of the lever has thereon a weight 26 and is connected by a hook 27 with a screen 28. The screen has the guides 29 movable on the 75 ways 30 which are carried by the door 31, and is movable across the aperture 32 in the door. The latter is pivotally connected by the hinges 33 and the pin 34 to bearings 35 of the frame 1, being held by a clip or button 80 37 which is carried by a pivot 38 connected to the frame.

The spur wheel 3, acting through the idler gears 39, 40 and 41, drives a pinion 42 on the shaft 43 which carries the sprockets 44. 85 These sprockets, with the contact rollers 45, feed the film, which is carried downwardly past the aperture 32 and through the way 46 to the bottom sprockets 47 on the shaft 48. The sprockets 49, which give the step by step 90 movement to the film, are carried by the shaft 50 journaled in the carriage 51 and having thereon a wheel 52. A revolvable shaft 53, journaled in the carriage, has fixed thereon a star wheel 54 with which the 95 wheel 52 engages so as to give to the sprockets 49 the desired step by step movement, in the usual manner. The shaft 53 has on one end thereof the fly wheel 55 and on the other end a pinion 56 which meshes with the spur 100 wheel 57. The wheel 57 and a spur wheel 58 fixed thereto are journaled on the spindle 59 carried by the carriage. The wheel 58 meshes with the spur wheel 4 which drives it, and, through the parts described, the 105 shaft 53. It is to be understood that the carriage 51 can be moved through the vertical range required without disengaging the pinion 58 and the gear 4 owing to the relatively large diameter of the latter and the 110

comparatively small range through which the carriage is moved, the teeth of the engaging wheels being made comparatively long and loose in mesh.

5. The shutter 60 is fixed to and revolved by the shaft 61 journaled in the carriage. The shaft is revolved by a miter gear 62 thereon through its engagement with a miter gear 63 fixed on the shaft 53, the shutter being placed so that it sweeps across the aperture 32 at right angles to the direction of travel of the film, which I have found to be a desideratum.

The carriage is adapted for vertical adjustment under control of the frame ways 64 and the guide rods 65 held on the frame by lugs 66. The position of the carriage is adjusted, to adjust the relation of the pictures on the film with reference to the aperture, by means of a link 67 pivoted to an upright 51' 15 on the carriage, an arm 68 pivoted to the link, a journaled rod 69 to which the arm is fixed, and a lever 70 fixed to the rod.

Having described my invention, I claim:—

1. In apparatus of the class described, mechanism for moving a film, a device having an aperture through which light is projected against said film, a screen having guides permitting its movement into positions for covering and uncovering said aperture, a handle which operates the mechanism for moving the film, and mechanism comprising a clutch whereby said screen is withdrawn from said aperture on turning said handle and is automatically returned on releasing said handle.

2. In apparatus of the class described, a screen, having one or more guides upon which it reciprocates a lever connected with said screen, a revoluble shaft, a wheel normally loose on said shaft, means for connecting said wheel and lever, a handle, mechanism comprising a clutch operated by said handle for engaging said wheel, and means whereby said clutch is automatically released on releasing said handle.

3. In apparatus of the class described, a movable screen, a revoluble shaft, mechanism whereby said screen is connected with said shaft, devices whereby said mechanism is clutched and unclutched in relation to said shaft, a handle, mechanism through which said handle operates said devices, film feeding mechanism, and gearing operated by said handle for operating said feeding mechanism.

4. In apparatus of the class described, a movable screen, a revoluble shaft, mechanism whereby said screen is connected with said shaft, clutching devices by which said mechanism is fixed and unfixed in relation to said shaft, a sleeve movable longitudinally in relation to said shaft to engage and disengage said clutching devices, a handle, and means whereby said handle revolves said shaft and moves said sleeve longitudinally.

5. In apparatus of the class described, a revoluble hollow shaft, a shaft movable longitudinally in said hollow shaft and fixed so as to revolve therewith, a handle having a limited motion of revolution with relation to said shafts, means whereby said handle moves one of said shafts longitudinally with relation to the other, a movable screen, and means connected with said shafts whereby said screen is operated.

6. In apparatus of the class described, a revoluble hollow shaft, clutching devices on said shaft, a shaft movable longitudinally in said hollow shaft and fixed so as to revolve therewith, means connected with the inner shaft whereby said clutching devices are operated, a handle having a limited motion of revolution with relation to said shafts, means whereby said handle moves said inner shaft longitudinally with relation to said outer shaft, a movable screen, and means connected with said shafts whereby said screen is operated.

7. In apparatus of the class described, a revoluble shaft a screen, means connecting said screen and wheel, a wheel loosely mounted on said shaft, clutching devices comprising a sleeve movable longitudinally on said shaft to engage and disengage said wheel, a second shaft fixed to said sleeve and movable longitudinally with relation to said first shaft, a handle for revolving said shafts, means whereby said handle moves said second shaft longitudinally with relation to said first shaft, and means for automatically withdrawing said sleeve and disengaging said clutch.

8. In apparatus of the class described, an outer shaft, an inner shaft movable longitudinally with relation to said outer shaft, a handle connected to said shafts, said handle being connected to said outer shaft by a cam and a pin permitting it limited movement along and around said shaft, a sleeve fixed to said inner shaft, a spring connected to said sleeve, a screen, and mechanism whereby said sleeve effects the operation of said screen.

9. In apparatus of the class described, a spur gear having a stationary axis, a handle connected to and revolving said gear, a movable carriage, a pinion carried by said carriage and engaged by said spur wheel, a spur wheel fixed to said pinion, a second pinion carried by said carriage and engaged by the last named spur wheel, a shutter carried by said carriage, and mechanism through which the last named pinion revolves said shutter.

In testimony whereof, I have hereunto set my name this 20th day of March, 1907, in the presence of the subscribing witnesses.

ORVILLE T. WEISER.
